Des. 220,084
Patented Mar. 9, 1971

220,084

CONTAINER FOR LIQUIDS

Eugene E. Goodrich, 819 S. Western Ave.,
Park Ridge, Ill. 60068

Filed Aug. 29, 1969, Ser. No. 18,907

Term of patent 14 years

Int. Cl. D9—07

U.S. Cl. D9—175

Fig. 1

Fig. 2

Fig. 3

Fig. 4

FIG. 1 is a perspective view of a container for liquids showing my new design, all of the sides being substantially the same in appearance as the sides which are visible in FIG. 1; the spout being retracted;

FIG. 2 is a top plan view;

FIG. 3 is a bottom plan view; and

FIG. 4 is a view like FIG. 1 showing the appearance when the spout is extended.

I claim:

The ornamental design for a container for liquids, as shown and described.
